UNITED STATES PATENT OFFICE

LOUIS D. ERBEN, OF ST. DAVIDS, PENNSYLVANIA.

DESIGN FOR A WOVEN FABRIC.

SPECIFICATION forming part of Design No. 22,945, dated December 5, 1893.

Application filed November 6, 1893. Serial No. 490,165. Term of patent 7 years.

To all whom it may concern:

Be it known that I, LOUIS D. ERBEN, a citizen of the United States, residing in St. David's, Delaware county, Pennsylvania, have 5 invented a new and original Design for a Woven Fabric, of which the following is a specification.

My design is fully shown in the accompanying drawings, in which—

10 Figure 1, represents a face view of a piece of the fabric; and Fig. 2, is a sectional view of the same on the line 2—2, Fig. 1.

The design comprises parallel stripes *a* and *b*, the stripes *a* having a plush like or tufted 15 surface, and the stripes *b* presenting a trans-

versely ribbed or corded appearance. The stripes *a* also project beyond the stripes *b* on both faces of the fabric, as shown in Fig. 2.

I claim—

The design for a woven fabric, substantially as described and as shown in the accompanying drawings.

In testimony whereof I have signed my name to this specification in the presence of two subscribing witnesses.

LOUIS D. ERBEN.
